F. HOERNER.
ADJUSTABLE VALVE SEAT FACER.
APPLICATION FILED MAR. 17, 1919.

1,349,153.

Patented Aug. 10, 1920

UNITED STATES PATENT OFFICE.

FRANK HOERNER, OF LOS ANGELES, CALIFORNIA.

ADJUSTABLE VALVE-SEAT FACER.

1,349,153.

Specification of Letters Patent. Patented Aug. 10, 1920.

Application filed March 17, 1919. Serial No. 283,205.

To all whom it may concern:

Be it known that I, FRANK HOERNER, a citizen of the United States, residing at Los Angeles, in the county of Los Angeles and State of California, have invented new and useful Improvements in Adjustable Valve-Seat Facers, of which the following is a specification.

My object is to make an adjustable valve seat facer and my invention consists of the novel features herein shown, described and claimed.

Figure 1 is a fragmentary section of an internal combustion engine showing an adjustable valve seat facer embodying the principles of my invention in use, the facer being shown in elevation.

Fig. 2 is a view in elevation upon an enlarged scale of the facer shown in Fig. 1, the upper and lower ends of the stems being broken away to economize space.

Fig. 3 is a vertical diametrical sectional detail of the facer head, the view being taken upon the line 3-3 of Fig. 4 and looking in the direction indicated by the arrows.

Fig. 4 is a top plan view looking in the direction indicated by the arrow 4 in Fig. 3.

Fig. 5 is a diametrical sectional detail as on the lines 5-5 of Figs. 2 and 6.

Fig. 6 is a horizontal section on the line 6-6 of Fig. 5.

Fig. 7 is a view analogous to Fig. 5 and taken on the lines 7-7 of Figs. 6 and 8.

Fig. 8 is a top plan view of Fig. 2.

Fig. 9 is a bottom plan view looking in the direction indicated by the arrow 9 in Fig. 2.

A facer head 1 is shown in detail in Fig. 3 and in Fig. 4 and the head is formed and machined from a solid circular piece of suitable steel. A base 2 is round in bottom and top plan and flat in diametrical cross section and has a screw threaded opening 3 extending upwardly from its lower face and a larger screw threaded opening 4 extending downwardly from its upper face, said openings 3 and 4 being in line.

A straight peripheral face 5 of the head 50 is considerably larger than the peripheral face of the base 2, there being an inclined face 6 connecting the lower end of the face 5 to the upper end of a face 7 of the base 2.

Radial slots 8 are formed across the head 55 from the upper flat face 9, the bottom of the slots forming the upper face 10 of the base

2. The slots 8 are evenly spaced apart and preferably there are eight slots radiating from the center. A bore 11 is formed downwardly from the face 9 concentric with the periphery 5 and in line with the screw threads 3 and 4 and concentric therewith, said bore 11 extending straight downwardly slightly beyond the lower edge of the periphery 5, and there being an inclined face 12 extending downwardly and inwardly from the lower end of the straight portion of the bore 11, and a straight face 13 extending downwardly from the lower end of the face 12 through the face 10 of the base, 70 said face 13 being slightly outside of the upper end of the screw threads 4.

An opening 14 is tapped downwardly from the face 9 substantially at the center of each of the housings 15 between the slots 8. Facer cutters 16 are mounted in the slots 8. Each cutter is made from a straight flat piece of suitable steel and has a lower edge 17 resting upon the face 10 at the bottom of the slot, a straight face 18 parallel 80 with the face 17, an inclined cutting face 19 extending upwardly and outwardly from the face 17, an inclined bearing face 20 parallel with the face 19 extending downwardly and inwardly from the face 18, and 85 vertical faces 21 and 22.

The cutters fit closely in the slots and are slightly higher than the housings 15, and the cutting face 19 extends slightly beyond the face 6 of the head 1.

A clamping plate 23 in the form of an annular ring fits upon the faces 18 of the cutters in opposition to the face 10 of the base, and clamping screws 24 are inserted downwardly through the clamping plate 23 90 into the tapped holes 14. The clamping plate 23 has radial slots 25 extending from its inner edge so that each section of the clamping plate is free enough to operate independently of the other sections when 100 the screws are operated. The slots 25 are directly above the cutters but are much narrower than the cutters so that any one cutter is controlled by two of the sections 26 between the slots 25.

An operating stem 27 has a wrench seat 28 upon its upper end for receiving a handle 29 or a bit stock brace or the like. The extreme lower end of the stem 27 is screwed into the threads 4 and jammed out enough 110 to hold during the operation of the tool. Screw threads 30 fit the screw threads 4.

2
only extending a short distance upon the stem. A neck 31 is formed above the screw threads 30 by reducing the stem, and then screw threads 32 extend upwardly from the 5 neck 31 a considerable distance. The stem 27 is reduced in size above the threads 32. An expanding head 33 is screwed upon the threads 32 and has a beveled face 34 upon its lower end extending through the clamp- 10 ing ring 23 and engaging the beveled faces 20 upon the cutters so that as the head 33 is screwed downwardly the cutters are moved outwardly and so that as the head 33 is screwed upwardly the cutters may be 15 moved inwardly.

The inner end faces 21 of the cutters may pass into the spaces formed by reducing the stem to produce the neck 31. In other words, at the start the cutters may be set 20 with their inner end faces 21 against the neck 31.

A wrench seat 35 is formed upon the upper end of the head 33 for manipulating the head.

25 A pilot stem 36 has a screw thread 37 upon its upper end to fit the screw thread 3 and a shoulder 38 below the screw thread to jam against the lower face of the head 1. The pilot stem 36 is adapted to extend downwardly through a valve opening 39 and fit in the valve stem bearing 40 so as to center the facer relative to the valve seat to be faced while the tool is in operation.

The operation is obvious. The engine casting 41 has a plugged opening 42 directly above a valve seat 43, and when it is desired to face the valve seat 43 the plug is removed from the opening 42, a pilot stem 36 is selected which will fit the bearing 40 and the 40 selected stem is placed in position by screwing into the threads 3, then the tool is inserted downwardly through the opening 42 with the pilot stem 36 in the bearing 40, and the tool may be operated in various ways, as 45 by the handle 29 or a brace or the like.

The stems 36 are to be made up in sets so that a stem may be selected to fit the bearing 40 of the engine to be operated upon, for instance, one valve stem bearing may be half an 50 inch and another five-eighths of an inch, etc.

Various changes may be made without departing from the spirit of my invention as claimed.

I claim:

55 1. In a valve seat facer, a head formed with radial slots in its upper face, cutters slideable in said slots, said head being provided with screw holes in its upper face between said slots, a plate fitting on the upper face of said head, said plate being provided with a central opening and with radial slots extending from said opening, said plate being also provided with screw holes between its slots adapted to register with the screw holes in said head, screws extending through the screw holes in said plate and screwing into the screw holes in said head to hold said plate on said head, a stem extending through said central opening in said plate secured in said head, an expanding head mounted on said stem for engaging said cutters and forcing them outwardly, and a pilot stem secured to the lower side of said head.

the screw holes in said plate and screwing into the screw holes in said head to hold said plate on said head, a stem secured in said head and extending through the opening in said plate, a thread on the lower portion of 70 said stem, an expanding head screwing on said stem thread for engaging said cutters to force them outwardly, a wrench seat on the upper end of said stem, and a pilot stem secured to said head adapted to fit in a valve 75 bearing.

2. In a valve seat facer, a head formed with radial slots in its upper face, cutters slideable in said slots, said head being provided with threaded screw holes in its upper 80 face between said slots, a plate fitting on the upper face of said head, said plate being provided with a central opening and with screw holes adapted to register with the screw holes in said head, screws extending through the holes in said plate and into the threaded holes in said head for holding said plate on said head over the upper edge of said cutters, a stem extending through the central hole in said plate and secured in 90 said head, an expanding head mounted on the lower portion of said stem for forcing said cutters outwardly, and a pilot stem secured to the lower side of said head.

3. In a valve seat facer, a head formed 95 with radial slots in its upper face, cutters slideable in said slots, said head being provided with screw holes in its upper face between said slots, a plate fitting on the upper face of said head, said plate being provided 100 with a central opening and with radial slots extending from said opening, said plate being also provided with screw holes between its slots adapted to register with the screw holes in said head, screws extending through the screw holes in said plate and screwing into the screw holes in said head to hold said plate on said head, a stem extending through said central opening in said plate secured in said head, an expanding head mounted on 105 said stem for engaging said cutters and forcing them outwardly, and a pilot stem secured to the lower side of said head.

4. In a valve seat facer, a head formed with radial slots in its upper face, cutters slideable in said slots, said head being provided with threaded screw holes in its upper face between said slots, a plate fitting on the upper face of said head, said plate being provided with a central opening and with screw holes adapted to register with the screw holes in said head, screws extending through the holes in said plate and into the threaded holes in said head for holding said plate on said head over the upper edge of said cutters, a stem threaded at its lower end extending through said central opening in said plate and screwing into said head, an expanding head mounted on said stem for engaging and forcing said cutters outwardly, 130

and a pilot stem secured to the lower side of said head.

5. In a valve seat facer, a head formed with radial slots in its upper face, cutters 5 slidable in said slots, means fastened in the upper face of said head for independently clamping the cutters in said slots, said means being provided with an opening, a stem secured in said head and extending through 10 said opening, a vertically movable expanding head mounted on said stem for engaging said cutters and forcing them outwardly, and a pilot stem secured in said head to fit in a valve bearing.

6. In a valve seat facer, a head formed 15 with radial slots in its upper face, cutters slidable in said slots, means removably fastened to the upper face of said head to hold said cutters in said slots, a stem secured in said head, an expanding head vertically 20 movable on said stem for engaging said cutters and forcing them outwardly, and a pilot stem secured in said head to fit in a valve bearing.

In testimony whereof I have signed my 25 name to this specification.

FRANK HOERNER.
